UNITED STATES PATENT OFFICE

134,067

DESIGN FOR A ROSARY

James McNamee, Edmond, Okla.

Application May 8, 1942, Serial No. 106,831

Term of patent 14 years

To all whom it may concern:

Be it known that I, James McNamee, a citizen of the United States of America, residing at Edmond, in the county of Oklahoma and State of Oklahoma, have invented a new, original, and ornamental Design for a Rosary, of which the following is a specification, reference being had to the accompanying drawing forming a part thereof.

The figure is a plan view of a rosary, showing my new design.

I claim:

The ornamental design for a rosary, as shown.
JAMES McNAMEE.
